United States Patent Office

Des. 233,900
Patented Dec. 10, 1974

233,900

ANIMAL FACE ACTION TOY

Albert Stubbmann, Franklin Lakes, N.J., assignor to Kohner Bros., Inc., East Paterson, N.J.

Filed Feb. 22, 1973, Ser. No. 334,544

Term of patent 14 years

Int. Cl. D21—01

U.S. Cl. D34—15 B

FIG. 1.

FIG. 2.

FIG. 3.

FIG. 4.

FIG. 1 is a front elevational view of a funny face toy showing my new design;

FIG. 2 is a top plan view thereof;

FIG. 3 is a rear elevational view thereof; and

FIG. 4 is a side elevation view thereof.

I claim:

The ornamental design for an animal face action toy, as shown.
